(57) **CLAIM**

The ornamental design for a liquid measuring and dispensing device, as shown and described.

DESCRIPTION

FIG. 1 is a front perspective view of a liquid measuring and dispensing device of the present invention;

FIG. 2 is a top plan view of the liquid measuring and dispensing device of FIG. 1, shown with a filler tube extending into the liquid measuring and dispensing device, wherein the filler tube is shown in phantom;

FIG. 3 is a bottom plan view of the liquid measuring and dispensing device of FIGS. 1 and 2;

FIG. 4 is a left side elevation of the liquid measuring and dispensing device of FIG. 1;

FIG. 5 is a front elevation of the liquid measuring and dispensing device of FIG. 1;

FIG. 6 is a right side elevation of the liquid measuring and dispensing device of FIG. 1;

FIG. 7 is a rear elevation of the liquid measuring and dispensing device of FIG. 1;

FIG. 8 is a front elevation of the liquid measuring and dispensing device of FIG. 1, shown mounted to a bottle with a siphon tube extending into the bottle, and wherein the bottle and the siphon tube are shown in phantom;

FIG. 9 is a front perspective view of another embodiment of the liquid measuring and dispensing device of the present invention with the device formed from a transparent material, shown with a filler tube extending into the liquid measuring and dispensing device, wherein the filler tube is shown in phantom;

FIG. 10 is a top plan view of the liquid measuring and dispensing device of FIG. 9;

FIG. 11 is a bottom plan view of the liquid measuring and dispensing device of FIG. 9;

FIG. 12 is a left side elevation of the liquid measuring and dispensing device of FIG. 9;

FIG. 13 is a front elevation of the liquid measuring and dispensing device of FIG. 9;

FIG. 14 is a right-side elevation of the liquid measuring and dispensing device of FIG. 9;

FIG. 15 is a rear elevation of the liquid measuring and dispensing device of FIG. 9; and,

FIG. 16 is a front elevation of the liquid measuring and dispensing device of FIG. 9, shown mounted to a bottle with a siphon tube extending into the bottle and wherein the bottle and the siphon tube are shown in phantom.
